(57) **CLAIM**

The ornamental design for a wire cage habitat, as shown and described.

DESCRIPTION

FIG. 1 is a front perspective view of the wire cage habitat showing our new design;

FIG. 2 is a front elevation view shown with the handle at the top of the wire cage habitat in an alternate configuration thereof;

FIG. 3 is a rear elevation view shown with the handle at the top of the wire cage habitat in an alternate configuration thereof;

FIG. 4 is a left side elevation view shown with the handle at the top of the wire cage habitat in an alternate configuration thereof;

FIG. 5 is a right side elevation view shown with the handle at the top of the wire cage habitat in an alternate configuration thereof;

FIG. 6 is a top plan view thereof; and,

FIG. 7 is a bottom plan view thereof.

The broken lines shown on the drawings are for the purpose of illustrating environmental structure and forms no part of the claimed design.
